(57) **CLAIM**

The ornamental design for a hair curler as shown and described.

DESCRIPTION

FIG. 1 is a front, right and top perspective view of a hair curler, showing my design.

FIG. 2 is a rear, left and bottom perspective view thereof.

FIG. 3 is an enlarged front elevation view of the hair curler.

FIG. 4 is an enlarged rear elevation view of the hair curler.

FIG. 5 is a left side elevation view of the hair curler of FIG. 1.

FIG. 6 is a right side elevation view thereof.

FIG. 7 is a top plan view thereof.

FIG. 8 is a bottom plan view thereof.

FIG. 9 is an enlarged view of the hair curler shown within the area designated as **9** in FIG. 1; and,

FIG. 10 is an enlarged view of the hair curler shown within the area designated as **10** in FIG. 1.

The dashed broken lines depict portions of the hair curler that form no part of the claimed design. The dot-dash broken lines in FIGS. 1, 9, and 10 depict the boundaries of the enlargements and form no part of the claimed design.

1 Claim, 10 Drawing Sheets
